(57) **CLAIM**

The ornamental design for tire, as shown and described.

DESCRIPTION

FIG. 1 is a front view of tire in accordance with the present invention;

FIG. 2 is a perspective view thereof;

FIG. 3 is another perspective view thereof;

FIG. 4 is another perspective view thereof;

FIG. 5 is another perspective view thereof;

FIG. 6 is a left view thereof; and,

FIG. 7 is an enlarged portion of side view thereof.

According to the present invention, a rear view is a mirror image of the front view thereof and a right view is identical to the left view thereof. The broken lines in the various Figures are for illustrating boundaries of the enlarged portion and form no part of the claimed design.
